UNITED STATES PATENT OFFICE.

JOHN O'LEARY, OF COHOES, NEW YORK, ASSIGNOR OF ONE-HALF TO
LE ROY VERMILYEA, OF SAME PLACE.

CONVERTIBLE CAR.

SPECIFICATION forming part of Letters Patent No. 661,921, dated November 13, 1900.

Application filed August 22, 1899. Serial No. 728,078. (No model.)

To all whom it may concern:

Be it known that I, JOHN O'LEARY, a citizen of the United States, residing at Cohoes, county of Albany, and State of New York, have invented certain new and useful Improvements in Convertible Cars, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures of the drawings.

Figure 1 of the drawings is a view in vertical cross-section of a convertible car embodying my improvements. Fig. 2 is a horizontal section taken on the broken line 2 2 in Fig. 1, showing a plan view of the lever which supports the sash and panel when raised. Fig. 3 is a horizontal section of one of the posts containing slideways for the sash, panel, and curtains, the section being taken on the broken line 3 3 in Fig. 1. Fig. 4 is a similar section taken on the broken line 4 4 in Fig. 1. Fig. 5 is a view in side elevation of one of the supplemental panels detached. Fig. 6 is a view of the lower corner of a curtain and a portion of the neighboring post containing the slideway for the same.

Referring to the drawings, the car-body comprises the floor 1, ceiling 2, roof 3, and a plurality of vertical posts 4, connecting the roof and ceiling with the floor. Between the roof and ceiling is provided a chamber 5, having a bottom opening 6 adjacent to the outer wall 7 of the chamber, through which opening the sash 8 and panel 9 are movable into and out of the chamber. The sash and panel may be of any desired form, but are preferably approximately straight and rigid and are adapted to fit into slideway-grooves formed in the vertical posts 4. The sash and panel are adapted when lowered to the position shown at the left-hand side of Fig. 1 to close the opening between two neighboring posts 50 on one side of the car from floor to ceiling and when raised up into the chamber to leave

an open way between said two posts and from floor to ceiling for the entrance and exit of passengers. When raised up into the chamber, the sash and panel are caused to assume 55 an inclined position, as shown at the right-hand side of Fig. 1, and in raising and lowering the sash and panel they are brought gradually from the position shown at one side of Fig. 1 to the position shown at the other 60 side of the same figure, and the bottom opening 6 must be made of a sufficient width to permit more or less inclination of the sash and panel while passing through such opening. As a means for closing said bottom opening 65 both when the sash and panel are raised and when they are lowered I provide the movable door 10, adapted to be secured across said opening and form apparently a part of the ceiling. This door may be of any known 70 form.

I have shown the door hinged at 11 and provided on its swinging end with a locking-bolt 12, which may be of any known form, adapted to enter a recess 13 in the neighboring post 75 when the door is closed, whereby the door is secured in a closed position, as shown in Fig. 1 at the left-hand side.

On account of the inclination which it is necessary to impart to the sash in moving 80 the same into and out of the chamber it is possible to make the sash tightly fit its slideway 14 only at the lower end, the slideway either being gradually widened toward the opening 6 on the bead 15, forming the inner 85 wall of the slideway, being wholly omitted, except for a short distance at the lower end of the slideway, as shown. As a means for supporting the upper end of the lowered sash I provide a flange or abutment 16 on the swinging end of the door adapted to engage the top of the sash and tightly hold the same when the door is closed, as shown at the left-hand side of Fig. 1.

The sash and panel may be guided in their 95 movements into and out of the chamber in any known manner. I have shown a guiding friction-roller 17, supported in bearings on the ceiling or inner wall of the opening 6, and the door 10 provided on its swinging end with 100 a similar friction-roller 18 and also provided with a stop 19, of any known form, to limit its

opening movement, whereby said rollers 17 and 18 form guides and roller-supports for the sash and panel when the same are being moved into and out of the chamber. The 5 door 10 is also provided with bearing-supports 20 for the roller-curtain 21, which may be of any known form, the bearing-supports and curtain-roller partaking of the swinging movements of the door. By this means the 10 curtain is permitted to occupy the same position in use, whether the sash is raised or lowered, and is not permitted to interfere with the movements of the sash. The lower end of the curtain may be provided with a guide 15 rod or plate 22, adapted to move in the slide-way-grooves 27 in the posts and be guided thereby, or any other known guiding means may be employed.

When it is desired to move the sash and 20 panel, the guide-plate 27 may be removed from the slideway-grooves by tilting the plate to the position indicated by dotted lines in Fig. 6, whereupon the curtain can be wholly wound upon its roller and swung, with the 25 door, out of the path of the sash and panels, as shown at the right-hand side of Fig. 1. The curtain is thus adapted to be used both as a light-shade when the sash is lowered and as either a light-shade or storm-curtain when 30 the sash is raised.

I have provided in the bottom of the chamber 6 a bed 23, mounted upon the springs 24 and adapted to receive and yieldingly support the sash and panel when raised, as shown 35 in Fig. 1 at the right-hand side, and I also provide a supporting-lever 25, pivoted at one end at 26 upon the outer wall of the chamber near its mouth and having its other end adapted to swing across said opening beneath 40 the lower ends of the sash and panel and prevent the same from descending through the opening 6 and from engaging the door 10. The swinging end of the lever is adapted to engage and rest upon a support 27 on the opposite 45 wall of the chamber, which support may be provided with a recess 28, adapted to form a seat for the end of the lever.

The car above described is equally adapted for use as either a summer or a winter car, 50 in cold or inclement weather the sash and panels being lowered to the position shown at the left-hand side of Fig. 1 to close the sides of the car and in warm and pleasant weather being raised to afford side entrance 55 and exits and free entrance of air. The construction permits of easy and rapid change from one style of car to the other, and when in use as an open car the same can be quickly closed in the event of a storm or when desired. When used as a winter-car, I provide 60 the supplemental panel 38, adapted to be supported just inside of and in close proximity to the panel 9, leaving a narrow air-space 29 between the two panels, which serves as a non-conductor of heat and contributes largely to 65 the warmth of the car.

The upper end of the supplemental panel

is secured by means of the offsets 30 on its upper end adapted to fit the curtain slide-way-grooves 37, the offsets being permitted 70 to enter said grooves through slots 31, formed in the inner walls of said grooves. The lower end of the supplemental panel may be secured to the floor of the car by means of screws 32 inserted through the bottom flange 33 on the 75 panel. The supplemental panel is provided with an abutment 34 on its upper end adapted to overlie and bear upon the top of the panel 9, and the panel 9 is in like manner provided with an abutment 35, adapted to overlie and bear upon a projection or abutment 36 on the lower end of the sash, whereby when the supplemental panel is screwed down to the floor of the car it serves to tightly hold to their 80 seats both the panel 9 and the sash, thereby 85 preventing rattling of the parts and making tight joints to prevent the entrance of the elements. In summer the supplemental panel may be removed from the car.

What I claim as new, and desire to secure 90 by Letters Patent, is—

1. In a convertible car, the combination with the car-body having between the roof and ceiling a chamber with a stationary outer side wall and a bottom opening formed wholly 95 by an aperture in the ceiling; of a sash and panel movable into and out of said chamber through said bottom opening; and a movable door for said opening, substantially as described.

2. In a convertible car the combination with the car-body having between the roof and ceiling a chamber with a bottom opening; of a sash and panel movable into and out of said chamber through said opening; means 105 for supporting the lower end of the lowered sash; and a movable door for said opening engageable with the upper end of the lowered sash, to support the same, substantially as described.

3. In a convertible car, the combination with the car-body having between the roof and ceiling a chamber with a bottom opening; of a sash and panel movable into and out of said chamber through said opening; and a 115 spring-supported bed in said chamber adapted to receive and support the raised sash and panel, substantially as described.

4. In a convertible car, the combination with the car-body having between the roof and ceiling a chamber with a bottom opening; of a sash and panel movable into and out of said chamber through said opening; a lever hinged to one of the chamber-walls and adapted to swing across said opening and forming 125 a support for the panels; and a support on the opposite chamber-wall for the swinging end of said lever, substantially as described.

5. In a convertible car, the combination with the car-body having between the roof and ceiling a chamber with a bottom opening of a sash and panel movable into and out of said chamber through said opening; a movable door for said opening; a stop for limiting

the opening movement of said door; and a friction-roller on the door, whereby the open door is adapted to support and form a guide for the sash and panel as the same are moved 5 into and out of said chamber, substantially as described.

6. In a convertible car, the combination with the car-body having between the roof and ceiling a chamber with a bottom opening; 10 of a sash and panel movable into and out of said chamber through said opening; a movable door for said opening; a curtain; and supports for the curtain mounted upon and movable with said door, substantially as de- 15 scribed.

7. In a convertible car, the combination with a roof, floor and ceiling constructed with a panel-receiving chamber having a fixed

outer wall and a bottom opening for said chamber formed by an aperture in the ceiling 20 adjacent to said outer wall of stationary vertical side ribs provided with panel-slideways defined on the outer side by a fixed stop or bead and leading to said chamber-opening; a panel movable in said slideways into and out 25 of said chamber; means for supporting the panel in said chamber; and a door attached to the ceiling and movable across said opening; substantially as described.

In testimony whereof I have hereunto set 30 my hand this 21st day of August, 1899.

JOHN O'LEARY.
